UNITED STATES PATENT OFFICE

LEON LOUIS MATHIEU, OF ROUEN, FRANCE, ASSIGNOR TO SOCIETE ANONYME DES HAUTS-FOURNEAUX ET FONDERIES DE PONT-A-MOUSSON, OF PONT-A-MOUSSON, MEURTHE-ET-MOSELLE, FRANCE

SAND-PACKING DEVICE FOR PIPE MOLDS

Application filed December 29, 1928, Serial No. 329,205, and in France April 27, 1928.

This invention relates to the manufacture of pipe molds, and more particularly socket pipe molds used for casting pipes by the centrifugal method. More specifically, the invention comprises improved means for the compression of sand in a suitable flask in one piece, the primary object of the invention being to provide for an apparatus adapted to work in a rapid and reliable manner, and to 10 deliver pipe molds in which the sand is properly compressed in all parts of the mold.

The characteristic features of the improved apparatus will be specified in the following description and more fully pointed 15 out in the claims.

In the accompanying drawings which are given solely by way of example:

Fig. 1 is a general elevational view of the apparatus.

Fig. 2 is a vertical section on a larger scale through the lower portion of the apparatus, the parts being shown in the position they assumed before clamping the flask in position.

Fig. 3 is a view corresponding to Fig. 2 showing the position of the parts during the sand filling.

Fig. 4 is a view analogous to Fig. 3, corresponding to the end of the compression of 20 the sand in the lower part of the apparatus.

In the form of construction herein represented, the tubular flasks 1 (Fig. 2) comprise a tubular body, an upper head 1^a and a lower head 1^b. They are provided at the centre 35 with a supporting sleeve 2 (Fig. 1) carrying trunnions 3 by which they can be taken up from the horizontal position by a hoisting apparatus and placed in the vertical position on a rotatable frame 4. The frame 4 is adapted 40 to receive a certain number of flasks, four for instance, and is rotatably supported upon one of the columns 5 of the packing tower. By rotating the frame 4, the flasks 1 may be successively brought at the centre of the 45 tower, as shown in Figs. 1 and 2, the top head 1^a of the flask to be packed with sand being then exactly below a centering cross-frame 6 provided on the tower and forming an abutment for the flask. Below the lower head 1^b 50 of the flask is mounted a double hydraulic

press or like apparatus shown in vertical section in Fig. 2, and comprising two pistons 7 and 8. The outer hollow piston 7 is movable in a fixed cylinder 9, to which the power fluid (water, steam, etc.) is admitted at 10, the exhaust being shown at 11. In the piston 7 is movable the inner piston 8, for which the admission takes place at 26 and the exhaust at 12.

The outer piston 7 carries the pattern 16 60 for the socket of the pipe, through the medium of an annular support 14, and a centering member 13. Suitable vibrators 15 are mounted on the latter.

The inner piston 8 carries at the top an 65 abutment or ejector 17 and is adapted to make contact with the lower end 16^a of the pattern 16.

The core 18 used for pressing the sand in the cylindrical part of the mold comprises a 70 cylindrical body provided at its lower end with a cylindrical head or mandrel 20, the cylindrical surfaces of the body and head being connected by a conical surface 18^a. The diameter D of the head 20 is equal to the 75 outer diameter of the pipe to be cast and the diameter d of the core body is slightly less. The abutment or ejector 17 on the inner piston 8 is adapted to press upwardly on a stud 20^a provided on the head 20.

With the flask 1 in the position shown in Figs. 1 and 2, the fluid is admitted at 10 and raises the piston 7, and the flask is thus centered on the member 13. As the piston continues to rise, the flask is lifted and centered by its upper head 1^a in the cross member 6. The core 18 is then placed within the flask and centered at the top in a removable centering ring 19 and at the bottom, its head 20 is centered in a corresponding bore of the 80 pattern 16.

In said position, the core rests with its lower head 20 upon the abutment 17 of the piston 8, and a clearance or space a b is left between the top of the piston 8 and the bottom 16^a of the pattern 16 carried by the centering member 13.

Sand is then filled from the top into the annular space between the flask and the core, and between the head 1^b and the pat- 100

tern 16. The sand may be supplied by the device shown in Fig. 1 and comprising a sand hopper 21, from which the sand is fed by a screw conveyor 22 into a vibrating sieve 23. Below the sieve, is a funnel member 24 which feeds the sand to the annular space between the core 18 and the ring 19. The vibrators 15 further the descent of the sand to the lower end of the mold.

Both the screw conveyor and sieve may be moved aside for the insertion and removal of the core 18 from the top.

The sand will thus completely fill the annular space *f* between the flask 1 and the core 18 and also the annular space *g* between the head 1^b and the pattern 16, which space corresponds to the socket end of the pipe. The inner piston 8 is then actuated, and in the first place the ejector 17 carried by said piston, raises the core 18 by an amount equal to the space *a*—*b*, whereby the sand is compressed by the conical part 18^a and cylindrical head 20 of the core at the junction between the spaces *f* and *g*.

The piston 8 in its upward stroke will then bring the pattern 16 into the elevated position shown in Fig. 4, whereby the sand is compressed in the space *g*. The core 18 is then raised further by the winch 25 (Fig. 1), which is accurately centered, whereby its conical part 18^a and cylindrical head 20 will compress the sand in the space *f*.

Obviously, the invention is not limited to the forms of construction hereinbefore specified which are given solely by way of example.

Having now described my invention what I claim as new and desire to secure by Letters Patent is:

1. A sand packing apparatus for socket pipe molds, comprising a flask member and a core for the pipe body, a head member and a pattern for the pipe socket, an abutment for the flask, an outer piston for bodily pressing the head member and the flask member against the abutment, an inner piston adapted to successively displace the core member and the pattern, means for actuating said pistons and means for inserting and removing the core member through the pattern and flask member.

2. A sand packing apparatus for socket pipe molds, comprising a vertically arranged flask member and a core for the pipe body, a head member and a pattern for the pipe socket, an abutment member above the flask, a supporting member for said head member and flask member, the core having a head and the pattern being centered between said supporting member and said head, vibrating means on said supporting member, means for feeding sand from the top to the annular space between the flask and the core, means for bodily pressing the supporting member, head member and flask member against the abutment, means for displacing the core through

the pattern and flask member, means for displacing the pattern in the head member and means for inserting and removing the core member through the pattern and flask member.

3. A sand packing apparatus for socket pipe molds comprising a flask member and a core for the pipe body, a head member for the pipe socket, means for pressing the sand in the body member, said means including a main ramming pattern axially movable lengthwise of the flask member, a movable head pattern for pressing the sand in the head member, means for moving said head pattern, a stationary abutment adapted to engage the end of the flask member opposite the socket and means for axially moving the flask and the head member and pressing them against said stationary abutment.

4. A sand packing apparatus for socket pipe molds comprising a flask member and a core for the pipe body, a head member for the pipe socket, means for pressing the sand in the body member, said means including a main ramming pattern axially movable lengthwise of the flask member, a movable head pattern for pressing the sand in the head member, means for moving said head pattern, a stationary abutment adapted to engage the end of the flask member opposite the socket, means for axially moving the flask and the head member and pressing them against said stationary abutment, said means including a power fluid driven piston carrying a centering piece for the socket end of the flask.

5. A sand packing apparatus for socket pipe molds comprising a flask member and a core for the pipe body, a head member for the pipe socket, means for pressing the sand in the body member, said means including a main ramming pattern axially movable lengthwise of the flask member, a movable head pattern for pressing the sand in the head member, means for moving said head pattern, a stationary abutment adapted to engage the end of the flask member opposite the socket, means for axially moving the flask and the head member and pressing them against said stationary abutment and adapted also to draw with it the head pattern.

6. A sand packing apparatus for socket pipe molds comprising a flask member and a core for the pipe body, a head member for the pipe socket, means for pressing the sand in the body member, said means including a main ramming pattern axially movable lengthwise of the flask member, a movable head pattern for pressing the sand in the head member, a stationary abutment adapted to engage the end of the flask member opposite the socket, means for axially moving the flask and the head member and pressing them bodily against said stationary abutment, said means comprising a power fluid driven piston

carrying a centering member for the socket end of the flask, the head pattern being slidably carried by said centering member whereby it may be moved axially together with said centering member, a second power fluid driven piston slidably extending through the first named piston which forms the cylinder for said last named piston and adapted to engage and move said head pattern independently of said centering member.

10 7. In a sand packing apparatus as claimed in claim 6, the further feature residing in that said first named piston is adapted to draw with it in its forward stroke said last mentioned piston.

15 8. A sand packing apparatus as claimed in claim 6, in which the means for moving axially the main ramming pattern includes a hoisting device, the provision of means adapted to cause said second piston to engage and move axially said main pattern on a determined length prior to engage and move the head pattern.

9. A sand packing apparatus for socket 25 pipe molds comprising a flask member and a core for the pipe body, a head member for the pipe socket, means for pressing the sand in the body member, said means including a main ramming pattern axially movable 30 lengthwise of the flask member, a movable head pattern for pressing the sand in the head member, means for moving said head pattern, a stationary abutment adapted to engage and center the end of the flask member opposite the socket, a centering piece for the socket end and means for axially moving centering piece, flask and head member so as to press the flask against said stationary abutment and center it at both ends.

40 10. A sand packing apparatus for socket pipe molds comprising a flask member and a core for the pipe body, a head member for the pipe socket, means for pressing the sand in the body member, said means including a main ramming pattern axially movable 45 lengthwise of the flask member, a movable head pattern for pressing the sand in the head member, means for moving said head pattern, a centering member for each of the 50 flask ends, one of said centering members being movable axially, and means for axially moving said centering member together with the head member and the flask so as to center the flask at both ends.

55 In testimony whereof I have signed my name to this specification.

LÉON LOUIS MATHIEU.
